[57] **ABSTRACT**

A marine autopilot system for ships in which the set course signal and the heading signal are supplied to a comparator which feeds a servomotor through an operational device to control the ship. In the present invention when the marine autopilot is automatically changing course, switching means change various constants and functions of the marine autopilot system and disconnect other elements which are unnecessary during course change.

MARINE AUTOPILOT SYSTEM INCLUDING MODE ENGAGEMENT FEATURES

BACKGROUND OF THE INVENTION

1. Field of the Invention

This invention relates to an automatic steering system, and more particularly to a marine autopilot system.

2. Description of the Prior Art

Generally, an automatic steering system has two principal functions. One is to hold a ship on a straight line along her set course. This function is required for long-distance navigation. The second function is to automatically change the ship's course. There are many occasions when the set course must be changed as for selecting the great circle route to a destination, for avoiding a collision with other ships, and for various other reasons. During an automatic course change, the ship should be steered to the newly set course without over-shoot, with the minimum number of steering operations and with minimum speed loss as quickly as possible.

Theoretically, holding a straight course is a steady response and a course change is a transient response.

Prior art autopilots have been designed and adjusted so as to enhance the course-keeping capability. In recent years, however, the size and speed of ships have increased and, as a result, the response of the ship to movement of the rudder exceeds the limits of manual steering operation. Therefore, in such ships it is almost impossible to employ conventional methods for changing course with manual steering operations and thus after the ship has been brought roughly to the set course, the manual steering operation is switched to automatic operation. For this reason automatic change of course has become of great interest. Further, a smaller number of operators are available due to the use of automatic navigation equipment and persons with little manual steering experience will often be utilized to do the steering operation, thus making course changes by automatic means more and more important.

Under limited conditions, in order that the transient and steady-state responses of an automatic control system be operated at optimum values, it is necessary to change the parameters of the control loop. The limited conditions herein mentioned result from the physical characteristics of the ship. For example, factors such as the rudder angle, the limit of the rudder angle and/or an upper limit of speed of the rudder movement. Also these conditions include problems of performance such as, for example, if the rudder is held at large angles very often for maintaining the ship on the set course, her sailing speed will be decreased due to drag on the ship. Also, frictional components of the steering gear would be rapidly worn out.

SUMMARY OF THE INVENTION

The performance of the marine autopilot system can be enhanced, if optimum response is obtained by the use of optimum parameters during course changes and while maintaining a fixed course.

Accordingly, one object of this invention is to provide a marine autopilot system which gives high performance.

Another object of this invention is to provide a marine autopilot system which allows the control

parameters to be switched to different values which optimum for changing course or maintaining a fixed course.

Other objects, features and advantages of this invention will become apparent from the following description taken in conjunction with the accompanying drawings.

BRIEF DESCRIPTION OF THE DRAWINGS

FIG. 1 is a schematic diagram, for explaining a conventional autopilot system;

FIG. 2 is a schematic diagram showing one example of a marine autopilot system of this invention;

FIG. 3 is a schematic diagram illustrating one example of a means for driving the principal part of the system of this invention exemplified in FIG. 2;

FIG. 4A is a connection diagram showing one concrete example of the part depicted in FIG. 3;

FIG. 4B is a schematic diagram showing a modification of one part of the connection diagram depicted in FIG. 4A; and

FIGS. 5 and 6 are schematic diagrams illustrating other examples of this invention.

DESCRIPTION OF THE PREFERRED EMBODIMENTS

For a better understanding of this invention a detailed description will be given first of the construction and function of a conventional marine automatic steering system with reference to FIG. 1. A heading signal ϕ of a ship 12 or the like derived from a compass 13 mounted thereon is supplied to an adder 1 and is compared with a set course signal ϕ_i fed to the adder 1. In the event that a deviation exists between the heading signal ϕ of the ship 12 and her set course signal ϕ_i , the adder 1 converts the deviation into an error signal ϕ_e and the resulting error signal ϕ_e is supplied to a weather adjustment device or unit 2. In the illustrated example the weather adjustment device 2 is in the form of a dead-zone circuit, which may be replaced with a filter or an attenuator. The weather adjustment device 2 serves to avoid over use of the helm which results from an increase in the number of steering operations caused by yawing of the ship under the influence of external disturbances in bad weather conditions. The error signal ϕ_e is applied to an integrator 3, a proportional amplifier 4 and a differentiator 5 connected in parallel and the resulting signals are combined together at an adder 6.

As is well-known, the autopilot controls the steering gear with the use of a rate signal $K\phi_e$ proportional to the turning speed of the ship in addition to the signal $K\phi_e$ proportional to the deviation between the actual ship's heading and the set course so as to stabilize a control loop including the ship. In some cases, the autopilot employs an integration signal in the control loop including the ship for controlling the steering gear with an integrated signal $K\int \phi_e$ together with the error and error rate signals in order to maintain the ship's heading on the set course ϕ_i .

The operational signal $K(\phi_e + \phi_e + \phi_e)$ thus obtained is applied as the command signal to a motor 9. This signal is first fed through a rudder angle limiting control mechanism 16, an adder 7 and an amplifier 8 before reaching motor 9. The motor 9 actuates a

rudder 14 through a gear mechanism 10. A feedback signal generator 11 is controlled by rotation of the output shaft of the motor 9 and produces a signal proportional to the steering angle. This signal is fed back to the input of the amplifier 8. Thus, the rudder 14 is driven to correspond to the operational signal in a minor control loop comprising the adder 7, the amplifier 8, the motor 9, the gear mechanism 10 and the signal generator 11.

Generally, the maximum angle of the rudder is limited by its mechanical construction but some rudders are provided with a mechanism which allows the rudder movement to be limited to an angle smaller than the maximum angle during automatic steering so as to increase safety. Such rudder angle control mechanism has response so as to be insensitive to normal rudder angles selected under normal steering conditions and prevents the rudder from suddenly being turned to the maximum angle causing sudden turning of the ship when the autopilot goes out of order.

It is the practice in the art to incorporate in the autopilot an alarm device or unit 15 including a buzzer or the like which raises an alarm when the ship's heading has deviated from its set course by a predetermined value. The alarm is given upon occurrence of the predetermined deviation between the ship's heading and the set course, so that during automatic course changes the alarm device continues to raise the alarm until the ship's heading approaches the newly set course. The alarm device is provided with a switch to prevent it from sounding during course changes of this type.

The problem is to bring the ship's heading to the newly set course without over-shoot and in the shortest possible time during an automatic course change which is a transient condition of the automatic steering system. Ideally different operational parameters in the operational device should be selected during course changes and course keeping. This would assure that autopilot characteristics detrimental to course changes would be removed during automatic course changes.

FIG. 2 illustrates one example of an automatic steering system of this invention provided with switch means for changing the autopilot parameters during course changes. In FIG. 2 similar reference numerals to those in FIG. 2 indicate similar elements which are identical in construction and in operation, and hence will not be described in detail for the sake of brevity.

In the figure those portions indicated by heavy lines are added to the conventional autopilot system according to this invention. In the illustrated example switches with contacts M₁ to M₄ are provided for respectively short-circuiting the weather adjustment device 2, the integrator 3, the differentiator 5 and the rudder angle limiting control mechanism 16. In addition, a switch with contact B is provided between the alarm device 15 and the output side of the adder 1.

The switch contact M₁ short-circuits the weather adjustment circuit 2. A slight increase in the number of steering operations is insignificant for the short time required for changing the course of the ship. Disconnecting the weather adjustment circuit 2 allows the ship to turn to the newly set course with accuracy. The contact M₁ is of particular utility when used with a dead-zone type weather adjustment circuit.

The switch contact M₂ resets the integrator 3. In the example of FIG. 2 the integrator 3 is made up of an operational amplifier 3₁ and a feedback capacitor 3₂, so that the output of the integrator 3 is reset by short-circuiting the integrated charge on the capacitor 3₂ with the contact M₂. When the ship has changed her course, the influence exerted upon the ship by the turning torque due to fixed external disturbances such as winds and so on sometimes will be opposite in direction to those before the course change. The switch contact M₂ allows the integrated output of the former course of the ship to be reset and an integrating operation of the newly set course is carried out.

The switch contact M₃ is employed for changing the rate time constant of the differentiator 5. In the example of FIG. 2 a differentiating capacitor 5₂ of the differentiator 5 is connected in parallel with a conventional differentiating capacitor 5₄ when the contact M₃ is closed during course change. The differentiating capacitor 5₂ is inserted into the differentiator 5 to increase the rate time constant. Reference numeral 5₁ indicates an operational amplifier of the differentiator 5. During an automatic course change it is necessary that sufficient rudder be applied for cancelling the great turning inertia of the ship and this is provided by a longer rate time than that for usual course keeping. This diminishes the amount of over-shoot and enables the ship to conform with a newly set course in the shortest time.

The switch contact M₄ short-circuits the rudder angle control circuit 16 for removing the small rudder angle limit. For changing the course a large rudder angle is required, as compared with the rudder angle for usual maintenance of the course and the control function of the rudder must be used fully for bringing the ship to the newly set course within a short time. The rudder angle limiting control mechanism must be removed to obtain rapid course changes.

The switch contact B serves to disconnect of the alarm device 15 temporarily. Since the alarm device 15 operates from the heading deviation signal ϕ_e during course changes, it would raise an alarm for every change of the course if not disconnected. It is desired to automatically reset the alarm device 15 while the course is being changed.

Further, the function of the autopilot can be enhanced by the provision of a contact device for holding various accessory circuits of the autopilot inoperative during the course change, though not shown in the example of FIG. 2.

Referring now to FIG. 3, a description will be given of one example of a device for controlling the switch contacts M₁ to M₄ and B of FIG. 2.

In FIG. 3 reference numeral 21 indicates a heading signal generating synchro incorporated in gyrocompass mounted on the ship. The output of the synchro 21 is supplied to a receiving synchro 22 in an autopilot. The synchro 22 is supplied with the heading signal ϕ of the ship. A deviation between the heading signal ϕ and a set course signal ϕ_i occurs in differential gear 28 and is converted by a synchro 23 into a deviation signal ϕ_e' . The resulting deviation signal ϕ_e' is converted by a differential modulator 25 into a DC signal ϕ_e , which is fed to an electric circuit 30 of the autopilot.

A course setting knob 24 of the autopilot is usually constructed so that it supplies an input through a clutch so as to avoid accidental changes which might occur if the operator should touch the knob. If a course is desired, the knob 24 is pressed to couple clutch members 27 and turned to rotate the differential gear 28. The knob 24 is always pressed upwardly by a spring 29 mounted between a stand 31 and the knob so that when the knob 24 is released after setting the course, the clutch members 27 disengage. At this time a contact of a micro switch 26 produces a pulse which represents that the ship has completed her course change. Since the time for closing the micro switch 26 for the course change may vary, the pulse signal derived from the micro switch 26 is applied through a memory circuit 32 to a timer 33 to actuate it. After a predetermined set time the timer 33 produces a reset signal to reset the memory circuit 32. The output of the memory circuit 32 is applied to a relay or a semiconductor switch 34 to drive it. The signal ϕe is supplied through an amplifier 35 to a time setting variable resistor 33₁ of the timer 33. This circuit is optional to this invention but performs the following operation to enhance the effect of the present system.

Within a range where the output $\phi e'$ of the synchro 23 remains unsaturated, the deviation signal ϕe is proportional to the course changing angle. The time required for changing the course of the ship also increases with an increase in the course changing angle. Accordingly, by automatically changing the set time of the timer 33 in accordance with the signal ϕe , the relay can be held operative for a certain period of time required for changing the ship's course.

FIG. 4A shows one example of the circuit construction of the system exemplified in FIG. 3. In FIG. 4 elements similar to those in FIG. 3 are identified by similar reference numerals for convenience of illustration. When the ship has changed her course, the micro switch 26 is closed to trigger the memory circuit 32 which may be a flip-flop circuit or a bistable multivibrator circuit. The output of the memory circuit 32 is supplied to the relay device 34 to actuate it. Respective contacts 34₁, 34₂, 34₃, . . . of the relay device 34 constitute switching units for the respective circuits in such a manner that the autopilot will respond well during the course change. One portion of the output of the memory circuit 32 is applied through a variable resistor R₃ and a resistor R₄ to an integrating amplifier 36₁ of the integrator 36. A diode D₅ having a breakdown point and a resistor R₅ are connected as the load of integrator 36. The diode D₅ may be a Shockley diode, SCR, SVS, UJT, or the like which permits the passage therethrough of a current when a voltage fed to it exceeds its breakdown voltage. When the output voltage of the integrator 36 goes above the breakdown voltage of the diode D₅, a voltage is produced across the resistor R₅ which is connected between the diode D₅ and ground and this voltage is applied as a reset signal to the memory circuit 32 to reset it. The variable resistor R₃ connected between the output end of the memory circuit 32 and the input end of the integrator 36 controls the integrator by altering its integrating time constant, thereby adjusting the operating time of the relay device 34. This allows adjustment to comply with the turning time which depends on the size and type of the

ship and this adjustment is made depending on the size and type of the ship in which the equipment is mounted.

A transistor Q₂ is operated by the signal ϕe from an input terminal 37. The input signal to the integrator 36 is adjusted by a change in the internal impedance of the transistor Q₂ between its collector C₂ and emitter E₂. Since the signal ϕe is a bipolar signal whose polarity varies with the direction of the deviation, the input signal ϕe is converted to one polarity by an inverter circuit 38 having a diode D₂ and connected between the input terminal 37 and the base B₂ of the transistor Q₂. Thus, when the signal ϕe is positive it flows into the base B₂ of the transistor Q₂ through a resistor R₁ and a diode D₁ which are inserted between the input terminal 37 and the base B₂ of the transistor Q₂ to lower the impedance of the transistor Q₂ between the collector C₂ and the emitter E₂. At the same time one portion of the input to the integrator 36 from the memory circuit 32 is bypassed to ground through a diode D₄ and the collector C₂ and the emitter E₂ of the transistor Q₂. When the signal ϕe is negative it is supplied through the resistor R₁ to the inverter circuit 38 and is thereby reversed in polarity becomes a positive signal, which is applied through the diode D₂ to the base B₂ of the transistor Q₂ to alter its impedance between its emitter E₂ and collector C₂, thereby changing the input to the integrator 36.

FIG. 4B is identical in construction with FIG. 4A except it uses a semiconductor switch as a substitute for the relay device 34. In the case where the respective contacts of the relay device 34 are required to be insulated from one another, a circuit such as shown in FIG. 4B is preferred. In the example of FIG. 4B the switch contacts M₁ and M₂ for short-circuiting the weather adjustment device 2 and the integrator 3 are respectively replaced by insulated-gate field effect transistors MOS₁ and MOS₂ and the output of the memory circuit 32 is applied to the gates MOS_{1G} and MOS_{2G} of the transistors MOS₁ and MOS₂ respectively. The weather adjustment device 2 and the integrating capacitor 3₂ of the integrator 3 are respectively respectively interposed between the source MOS_{1S} and drain MOS_{1D} of the transistor MOS₁ and between the source MOS_{2S} and drain MOS_{2D} of the transistor MOS₂. With such an arrangement, when the output of the memory circuit 32 is applied to the gates MOS_{1G} and MOS_{2G} of the transistors MOS₁ and MOS₂, the weather adjustment device 2 and the integrator 3 are respectively short-circuited by the transistors MOS₁ and MOS₂ which are rendered conductive and when the input to their gates is removed the shorting circuits are cut off. Accordingly, these transistors MOS₁ and MOS₂ perform exactly the same function as the relay device 34 of FIG. 4A. Although the example of FIG. 4B has been described in connection with the case where only the switch contacts M₁ and M₂ of the relay device 34 of FIG. 4A depicted in FIG. 2 are replaced with the insulated-gate field effect transistors, it will be understood that the switch contacts M₃, M₄ and B may have insulated-gate field effect transistors substituted for them.

In the event that the circuits such as the weather adjustment device and so on to be short-circuited need not be insulated from one another, conventional transistor switching circuits may be used.

FIG. 5 illustrates a modified form of this invention, in which reference numerals similar to those in FIG. 3 indicate similar elements. In the present example the deviation signal ϕe is used as a trigger signal representing a course change. The output $\phi e'$ of the synchro 23 is applied to a demodulator 25, whose output signal ϕe is fed to a comparator 45. The comparator 45 produces an output when the input signal ϕe exceeds a certain set value. The output of the comparator 45 is applied to the memory circuit 32 to trigger it, causing the circuit 32 to start the timer 33 and driving the semiconductor switching device or the relay device 34. Also, the output of the timer 33 is fed back to the memory circuit 32 as a reset signal. The system shown in FIG. 5 is advantageous in that it can be triggered in a pure electronic manner.

FIG. 6 shows another modification of this invention, in which reference numerals similar to those in FIG. 5 designate similar elements. This example is simpler in construction than that of FIG. 5 in that the signal ϕe from the demodulator 25 is applied to the comparator 45 to control its set level only and the relay device 34 is directly driven by the output of the comparator 45.

It will be apparent that many modifications and variations may be effected without departing from the scope of the novel concepts of this invention.

We claim as our invention:

1. A marine autopilot system for a ship for operating in a fixed course holding mode and a turn to a new course mode comprising:
a servo motor connected to the rudder of said ship to control it;
a course setting knob;
means for producing an error signal corresponding to the deviation between a set course and the ship's heading and set course setting knob connected thereto;
an operational means connected between said servo motor and said means for producing an error signal and including a weather adjustment device;
an integrator, a differentiator and a rudder angle limit means;
a first switch mounted adjacent said course setting

5 knob and actuated thereby when said course setting knob is operated to set a new course; a memory device connected to said first switch and producing an output each time said first switch is actuated for a time period until said memory is reset;

10 a variable timer receiving an input from said memory and supplying a delayed output to said memory to reset it, said means for producing an error signal supplying an input to said variable timer to control the delay between the timer's input and output; a second switch connected in parallel with said weather adjusting device; a third switch connected to said integrator for disconnecting it; a fourth switch connected to said differentiator for changing the response; and switch actuating means receiving an input from said memory and connected to actuate said second through fourth switches such that during a turn to new course mode said weather adjusting device and integrator are disconnected, and said differentiator has a different response than during said course holding mode.

15 2. A marine autopilot according to claim 1 further including:

a fifth switch with one side connected to said means for producing an error signal; and an alarm connected to the other side of said fifth switch, and said switch actuating means connected to open said switch during turn to new course mode.

20 3. A marine autopilot according to claim 2 further including:

a rudder angle limiting means forming a part of said operational means; and a sixth switch connected in parallel with said rudder angle limiting means and said switch actuating means connected to close said sixth switch during turn to new course mode.

25 4. A marine autopilot according to claim 1 wherein said second and third switches are field effect transistors.

* * * * *
